VISE TYPE ELECTRICAL CONNECTOR

Marvin Lee, Rye, N. Y., assignor to Burndy
Engineering Co. Inc., a corporation of New
York

Application June 17, 1939, Serial No. 279,592

6 Claims. (Cl. 24—263)

This invention relates to vise type electrical connectors which are often used for clamping wires or cables and are especially useful for making connections between overhead distribution conductors and service wires. Ordinarily, such connectors consist of two clamping jaws, assembled in the general form of a vise and drawn together by means of a screw. This invention is an improvement on previous forms of this device.

It is very desirable in an electrical connector to have the wires which it clamps completely enclosed therein. To accomplish this in vise-type connectors of the character herein disclosed, the generally used expedient is to have one clamping jaw overlap the other. In order to open this overlap for insertion of the wires into the connector means turning the screw several times to loosen it, and also several times in the opposite direction to tighten it. This procedure is inconvenient, especially where it occurs on top of a pole or in a similar awkward location. To avoid this unnecessary loosening and tightening of the screw is the principal object of this invention.

This object is obtained by having one of the jaws swing back or rotate in such a manner as to permit insertion of the wires into the other jaw. Such rotation or swinging is done with the screw as the hinge pin, thus eliminating the necessity of disengaging either jaw from the screw.

The moving jaw should be prevented from swinging forward too far or, alternatively, rotating in the wrong direction. This is an additional object of my invention.

I accomplish this object by the use of stops. Thus, jamming of the connector, while installing is eliminated.

When the screw is tightened there is a tendency for the jaws to bend open because of the cantilever forces exerted on them. This in turn, tends to bend the screw. A further object, therefore, is to provide means whereby this tendency to bend the screw will be eliminated. This object is attained by interlocking the jaws in such a fashion as to absorb the cantilever stresses. The bearing points of the jaws on each other are located at the top and bottom of each jaw respectively. This wide separation of the bearing points keeps the jaws in alignment and prevents bending of the screw.

I accomplish these and other objects and obtain my new results as will be apparent from the device described in the following specification, particularly pointed out in the attached claims

and illustrated in the accompanying drawing, in which:

Fig. 1 shows a side view of one form of the device.

5

Fig. 2 is a rear view of the same connector.

Fig. 3 is a top view.

Fig. 4 is a cross-sectional view.

Fig. 5 is a side view of another form of the connector showing the clamping jaw in closed position.

10

Fig. 6 is a rear view of the same connector with a partial section to show the internal construction.

15

Fig. 7 is a side view, in open position.

Fig. 8 is a cross-sectional view of the connector taken along line 8—8 in Fig. 5.

20

In the drawing, Figs. 1 to 4, an embodiment of my invention is shown consisting of a stationary jaw-member 10, a movable jaw-member 20, both positioned about and compressing conductor 30, 20 by means of bolt 40.

25

The stationary jaw-member comprises a top section 11, two side sections 12, a short reinforcing back section 13, and a hook-shaped jaw 14, extending from the front and top section 11.

25

The back section 13 is cut out as at 15, to permit the movable member to rotate therethrough, about the bolt 40 as a hinge, as will be hereinafter explained. Aperture 16 in the top side permits the bolt to slide freely therein, the head 41 reacting against the top section 11.

30

One of the conductors 30 is seated on the V shaped groove 17 of the jaw 14.

The movable jaw member 20 is formed with longitudinally extending rails 21, on each of sides 22, riding in corresponding grooves 18 of the stationary jaw-member 10.

35

A threaded aperture 23 extends longitudinally through the movable member 20 for entrance of the bolt 40.

40

On the lower end of the front side 24 of movable member 20, a V shaped jaw 25 protrudes a distance approximately equal to the greatest diameter of conductor which can be accommodated in jaw 14 of the stationary member 10. 45 The jaw 25 can be longitudinally moved within jaw 11 to compress the conductors securely, as shown in Fig. 1; jaw 14 having approximately the same length as member 10.

45

The jaw 25 is wider than any part of member 20 having the same width as the stationary member 10 (see Fig. 2), which increased width acts as a guide over cut-out 19 of member 10 and insures that the two jaws will be in operative relationship to each other.

50

55

When jaw 25 is propelled past the stationary member 10 by the rotation of bolt 40, the opening 15 in back wall 14 of the stationary member enables the entire movable member to be rotated 5 backwards about the head 41 of the bolt 40, as shown in Fig. 4. Thus, the jaw 25 need not be propelled longitudinally until it provides a space sufficient to allow a conductor to enter, but may be rotated in a transverse direction to expose the 10 mouth of jaw 14, permitting the conductor to be inserted.

The saving in bolt rotation is approximately that of the conductor diameter.

When the conductors are inserted into the 15 mouth of jaw member 14, the movable member 20 is restored to its operative position and the bolt 40 tightened. The extending sides of jaw 25 ride on the front edges of side walls 12, and rails 21 engage grooves 18. Thus the stresses occasioned by tightening the jaws about the conductors, and causing a bending moment are absorbed 20 by the sliding surfaces of the members, and not by the bolt.

In the modification shown in Figs. 5 to 8, the 25 movable jaw member 20a, is rotatably mounted on stationary jaw member 10a by means of bolt 40a.

When the bolt propels jaw member 20a to the point where jaw 25a passes jaw 14a and the 30 mouth of the jaw is opened, the top edge 26a of movable member 20a, is propelled past guide 15a.

The stationary member is provided with semi-cylindrical walls 12a forming channels 18a, and the movable member with semi-cylindrical walls 35 22a forming rails 21a.

When the guide 15a is passed, the movable member may be rotated about the bolt 40a as an axis. At the lower front end of one of the side walls, 12a, a stop 13a is formed which permits the movable member 20a to rotate in one direction only. Thus when it is desired to open the mouth of jaw 14a for entrance of conductors 30a, the jaw 25a is propelled by the bolt until the jaws just pass one another whereupon jaw 25a 45 may be rotated backwards as shown in Fig. 7.

The remaining reference numerals indicate parts corresponding to those described in the previous modification.

From the foregoing it is apparent that my modifications are simpler and quicker to install than 50 previous types.

Furthermore, I am able to obtain a quick installation of the conductors without placing a bending movement on the bolt, an extremely important element of my design and an important 55 object of my invention.

In addition, I provide a connector which is a unitary assembly and can be installed on cables or wires without removing any of the constituent parts from the unitary assembly. The parts 60 themselves require a minimum of machining and are inexpensive to manufacture.

By my definition, the movable jaw member is that member that moves with respect to the 65 head of the bolt.

I have thus described my invention, but I desire it understood that it is not confined to the particular forms or uses shown and described, the same being merely illustrative, and that the 70 invention may be carried out in other ways without departing from the spirit of my invention, and, therefore, I claim broadly the right to employ all equivalent instrumentalities coming within the scope of the appended claims, and by

means of which, objects of my invention are attained and new results accomplished, as it is obvious that the particular embodiments herein shown and described are only some of the many that can be employed to attain these objects and 5 accomplish these results.

What I claim and desire to secure by Letters Patent, is as follows:

1. A clamping device comprising a stationary member having a jaw; a movable member having 10 a jaw; a bolt in threaded relationship with respect to the movable member for drawing the two jaws together about the object to be clamped by rotating said bolt; means for keeping the movable member in sliding engagement with the stationary member; and means for permitting one jaw to be moved with respect to the other, independently of the threaded rotation of the bolt.

2. A clamping device comprising a stationary 20 member having a jaw; a movable member having a jaw; a bolt in threaded relationship with respect to the movable member for drawing the two jaws together about the object to be clamped by rotating said bolt; means for keeping the movable member in sliding engagement with the stationary member; and means for permitting one jaw to be rotated with respect to the other about the bolt as an axis.

3. A clamping device comprising a stationary 30 member having a jaw; a movable member having a jaw; a bolt in threaded relationship with respect to the movable member for drawing the two jaws together about the object to be clamped by rotating said bolt; means for keeping the movable member in sliding engagement with the stationary member; and means for permitting the movable member and the bolt to be rotated in a 35 unitary assembly with respect to the stationary member.

4. A clamping device comprising a stationary member having a jaw; a movable member having a jaw; a bolt in threaded relationship with respect to the movable member for drawing the two jaws together about the object to be clamped by 40 rotating said bolt; means for keeping the movable member in sliding engagement with the stationary member; means for disengaging the two members; and means for permitting one jaw to be rotated with respect to the other about the 45 bolt as an axis.

5. A clamping device comprising a stationary member having a jaw; a movable member having a jaw; a bolt in threaded relationship with respect to the movable member for drawing the two jaws together about the object to be clamped by 50 rotating said bolt; means for keeping the movable member in sliding engagement with the stationary member; means for disengaging the two members; and means for permitting the movable member and the bolt to be rotated in a 55 unitary assembly with respect to the stationary member.

6. An electrical connector comprising a stationary member having a jaw; a movable member having a jaw; a bolt in threaded relationship with respect to the movable member; for drawing the two jaws about an electrical conductor, by rotating said bolt; means for permitting one jaw to be moved with respect to the 60 other, independent of the threaded rotation of the bolt, and stop means for enabling said jaw to be so moved in one direction only.

MARVIN LEE.
